BURNER

Richard S. Moore, Dallas, Tex., assignor, by
mesne assignments, to Guiberson Oil Heater
Company, Grand Prairie, Tex., a corporation
of Texas

Application May 7, 1937, Serial No. 141,309

10 Claims.

(Cl. 158—91)

This invention relates to new and useful improvements in burners.

One object of the invention is to provide an improved burner which is adapted to burn a hydrocarbon liquid and may be readily installed in any type of heater or heating unit.

An important object of the invention is to provide an improved burner wherein a hydrocarbon liquid is utilized as fuel, the construction of the burner being such that the liquid is vaporized and the vapors, rather than the liquid itself, are burned, which makes for substantially complete combustion, resulting in increased heating efficiency as well as minimization of carbonizing and smoking.

Another object of the invention is to provide an improved hydrocarbon liquid burner wherein the liquid is first vaporized within a vaporizing chamber and the vapors are then admixed with air to form a combustible mixture, the air to the vaporizing chamber being restricted whereby a combustible mixture is not present in the vaporizing chamber and the flame or burning is thus located out of said chamber, wherein the liquid itself does not burn, which eliminates smoking, as well as carbon deposits; the burning of the vapors producing a hotter flame and thus, resulting in more efficient heating.

Another object of the invention is to provide an improved burner of the character described, wherein the flame is concentrated at the center of the heating unit wherein the burner is mounted, whereby said unit is particularly adapted for use in cooking, or similar purpose; there being provision made for insulating the combustion chamber so that heat radiation is reduced to a minimum.

A still further object of the invention is to provide an improved burner of the character described which is constructed so that the flame of the burning vapors may be spread, so that when the burner is applied to the usual type floor heater, an even distribution or radiation of heat is had.

A construction designed to carry out the invention will be hereinafter described, together with other features of the invention.

The invention will be more readily understood from a reading of the following specification and by reference to the accompanying drawings, in which an example of the invention is shown, and wherein:

Figure 1 is a transverse, vertical, sectional view of a burner, constructed in accordance with the

invention and applied to an open flame heating unit,

Figure 2 is a horizontal, cross-sectional view, taken on the line 2—2 of Figure 1,

Figure 3 is a horizontal, cross-sectional view, taken on the line 3—3 of Figure 1,

Figure 4 is a transverse, vertical, sectional view of a modified form of burner, applied to a floor heating unit,

Figure 5 is a horizontal, cross-sectional view, taken on the line 5—5 of Figure 4,

Figure 6 is a view, similar to Figure 4, showing still another form of burner,

Figure 7 is a horizontal, cross-sectional view, taken on the line 7—7 of Figure 6, and

Figure 8 is a horizontal, cross-sectional view, taken on the line 8—8 of Figure 6.

In the drawings, the numeral 10 designates a cylindrical burner housing having a bottom 11 from which supporting legs 12 depend, whereby the housing may rest on a floor, or other support. A cylindrical casing 13 having a curved bottom is disposed axially within the housing and rests on the bottom thereof. The top of the casing is spaced from the top of the housing and is formed with an axial opening 14 therein. The interior of the casing 13 forms a vaporizing chamber A and the fuel, which may be a hydrocarbon liquid, is introduced into the chamber through an inlet pipe 15 which extends radially through the walls of the housing and casing, and which has its inner end terminating within the chamber at the bottom thereof.

The inlet pipe has a suitable control valve 16 connected therein and the outer end of said pipe is curved upwardly and connected into a bowl 15'. A fuel supply receptacle or container 16' is inverted within the bowl and provides a constant supply of liquid fuel to the chamber A. The valve 16, of course, regulates the flow through the pipe.

Air is supplied to the chamber A through a conduit 17 which extends through the wall of the housing 10. This conduit is arranged to be closed by a cap 18, as will be explained. Additional air inlet openings 19 are formed in the wall of the casing 13, whereby air from the interior of the housing 10 may enter the chamber. The air flows into the housing 10 through openings 20 in the top of said housing. Besides the conduit 17 and openings 19, air may flow into the upper end of the chamber A through a radial pipe 21 which extends from the wall of the casing to the center thereof. As is clearly shown in Figures 1 and 3, air from the interior of the housing

10, through the pipe 21 and outwardly from the inner end of said pipe. This inner end of the pipe is provided with an upwardly directed elbow 22 which directs the air upwardly and out of the chamber through the axial opening 14 in the top thereof. The inlet of air through the pipe 21 in an upward direction aids the formation of a suction at the opening 14 in the chamber A, which draws the air and vapors in the chamber upwardly therefrom, as will be explained.

15 A perforated sleeve 23 surrounds the opening 14 in the upper end of the casing 13 and extends upwardly therefrom, terminating against the underside of the top of the housing. If desired, this sleeve may be made integral with the casing 13 and since it has a plurality of perforations 24 therein, it is manifest that air from the interior of the housing 10 may enter the sleeve.

The top of the housing 10 is formed with an axial opening 25 which is in alignment with the sleeve 23 and opening 14 in the casing 13, whereby the upward flow of air is directed. An upwardly extending collar 26 surrounds the opening 25 and this collar and the sleeve 23 form the combustion chamber, as will be explained.

20 Any suitable heating unit may be mounted above the burner housing 10 and in Figure 1 an open flame heater or cooker is shown. This heater comprises a cylindrical casing 27 which has its bottom resting on upwardly projecting lugs 26' formed on the upper end of the collar. The lugs act to space the top of the collar from the bottom of the heater so as to permit air to enter therebetween. The collar, of course, acts to space the bottom of the heater from the top of the housing 10 whereby air may enter therebetween and thence flow through the openings 20 in the top of the housing. The bottom of the heater housing has an axial opening 28 in alignment with the openings 25 and 14 and sleeve 23, and a cylindrical pipe or flue 29 extends axially and vertically through the casing 27 from said opening 28 to an outlet opening 30 in the top of the casing. The flue is smaller in diameter than the casing 27 whereby an annular air space or chamber B is formed therebetween. Air is admitted to this space through openings 31 in the top and bottom thereof, and said space acts as an insulating chamber to prevent the exterior of the heater casing 27 from becoming too hot and thereby reduces radiation to a minimum. Surrounding the lower end of the heater casing and terminating in a plane below the top of the housing 10 is an annular depending skirt 32'. The skirt is spaced from the exterior of the burner housing, as is clearly shown in Figure 1, and the air entering the space between the burner and heater must flow beneath the skirt, as indicated by the arrows.

25 In operation, the liquid fuel is supplied to the vaporizing chamber A through the pipe 15. The arrangement of the inverted fuel supply receptacle 16' maintains a constant level of liquid within the lower portion of the curved bottom of the casing 13. To ignite the burner, the cap 18 is removed and a torch or flame inserted through the conduit 17. Sufficient air is supplied through the conduit 17 to permit the liquid itself to ignite and burn. The liquid in the bottom of the chamber A is permitted to burn until such time as the walls of the casing 13 become heated, at which time the cap 18 is again placed into the end of the conduit 17. This cuts off the air supply to the chamber A through the conduit 17 and the air which is entering the

30 openings 19 in the walls of the casing 13 is not sufficient to promote combustion within the chamber A and therefore after the cap 18 closes said conduit, the burning of the liquid in the bottom of the chamber is stopped. Due to the heating of the chamber A by the burning of the liquid fuel, as has been explained, vapors rise off the body of fuel and pass upwardly through the opening 14 in the top of the casing and into the sleeve 23 and collar 26. These rising vapors tend to create a suction at the opening 14 and this suction is increased by the air emitting from the pipe 21 and elbow 22.

35 A much greater amount of air is present within the sleeve 23 and collar 26 due to the numerous perforations 24 in said sleeve and also due to the upwardly directed stream from the pipe 21 and therefore as this air admixes with the rising vapor, a combustible mixture is obtained. This mixture is ignited and burns within the sleeve 23, collar 26 and also within the flue 29 which extends vertically through the heater 27. Therefore it will be seen that the combustion chamber is formed at a point above the chamber A and the flame created by the burning mixture of vapors and air rises in the flue 29. The heat from the burning vapors is sufficient to keep the chamber A heated so that the liquid fuel therein continues to vaporize and these vapors are drawn upwardly into the combustion chamber and admixed with the incoming air. It is pointed out that the air not only comes into the combustion chamber through the perforations 24 in the sleeve but also passes therewith between the lugs 26' which support the heater casing 27. The flame is thus confined within the flue 29 and within the collar and sleeve therebelow and manifestly, the flue will become heated. To insulate the exterior wall of the heater casing 27, there is constant circulation of fresh cool air in the annular space or chamber B around the flue and this air space serves to insulate the exterior walls of the casing from the flue, whereby they do not become overheated and radiation of heat is reduced to a minimum.

40 By adjusting the hand valve 16 in the line 15, the flow of fuel into the chamber A may be positively controlled and if more or less of the fuel is within the chamber, more or less vaporization will occur. Of course, if more vapors rise into the combustion chamber, an increased heat will be had and by adjusting the hand valve 16, the heating may be readily controlled. It is pointed out that under ordinary operating conditions, there is not sufficient air introduced into the chamber A to bring about combustion but it is only when the conduit 17 is open that enough air to permit burning of the liquid fuel itself is introduced. The air which is introduced through the openings 19 merely aid in conducting the vapors rising from the liquid fuel to move upwardly into the combustion chamber where they may be admixed with a sufficient amount of air to produce a combustible mixture.

45 In Figures 4 and 5, a modified form of the invention is shown. In this form the casing 13 and its associate parts are substantially the same as in the first form. However in place of the central opening 14 in the top of the casing, an enlarged opening 32 is formed in said casing. This opening is surrounded by a flanged collar 33 which has perforations 34 in its vertical side. A second flanged collar 35 similar to the collar 33 extends upwardly from the opening 33' in the collar 33 and is provided with a

plurality of perforations 36 which admit air from the interior of the housing 10. It is noted that the number of perforations 36 in the collar 35 are greater than the number of perforations 34 in the collar 33 whereby a greater amount of air is introduced thereinto. The perforated sleeve 23 is mounted on the uppermost collar 35 and has a plate 37 supported thereon. The plate has a central opening 38 which registers with the opening 28' in the lower end of a heater housing 29'. The housing 29' rests on lugs 39 which extend upwardly from the plate 37. The plate 37 also forms the upper end of the housing 10' and the collar 26 is eliminated in this form. The plate is provided with inlet openings 40 to permit air to enter the interior of the housing 10'. The flue 29 which is shown in the first form, is not present in the form shown in Figure 4 but is entirely eliminated, while an outlet pipe 41 extends from the upper end of the housing 29'.

The operation of this form is substantially the same as that of the first form in that the liquid fuel is first ignited by removing the cap 18 from the conduit 17. Closure of the conduit 17 causes the flame to be transferred to the vapors rising from the liquid fuel. The air necessary to make a combustible mixture is introduced and admixed with the vapors within the flanged collars 33, 35 and the sleeve 23. Since the openings or perforations increase as the vapors rise toward the sleeve 23, it will be evident that the air is gradually increased in the mixture as the vapors rise toward the openings 28' in the heater housing 29'. The flame from the burning vapors will of course rise within the heater housing 29' and will serve to heat the interior thereof. The heating of this interior will of course heat the wall of the casing 29' and will by radiation of heat from said wall heat the room in which the unit is placed.

In Figures 6 to 8 still another form of the invention is shown. In this form instead of concentrating the flame of the burning mixture at the central portion of the heater casing, said flame is spread to some extent whereby a more even distribution of the heat within the casing 29', is had. In this form, the structure is very similar to the structure of the form shown in Figures 1 to 3 in that the chamber A and its associate parts are substantially the same. Instead of the inlet pipe 21, a circular pipe 43 is located axially at the upper end of the chamber and this circular pipe is supplied with air through radial pipes 44 (Figure 8) which lead from the interior of the casing 10a. A perforated sleeve 23', similar to the sleeve 23, extends upwardly from the casing 13 and surrounds the opening 13' in the top thereof. It is noted that the sleeve 23' has a larger diameter than the sleeve 23. A plate 45 rests on the upper end of the sleeve 23' and has lugs 46 on which the bottom of the heater casing 29' is supported. The plate 45 forms the top of the housing 10a and has an axial perforated sleeve 47 depending therefrom. This sleeve has a smaller diameter than the sleeve 23' and has its lower end disposed within the circular pipe 43. Openings 48 are formed in the plate and communicate with the annular space between the sleeves 23' and 47, while an axial opening 49 of a larger diameter than the openings 48 is located in the plate above the inner sleeve 47. The bottom of the heater casing or housing 29' is formed with a plurality of

openings 50 which are in vertical alignment with the openings 48 in the plate.

With this arrangement, the operation of this form is obvious. After the chamber A has been properly heated by the burning of the liquid fuel itself, the cap 18 is inserted into the conduit 17 to close the same whereby the flame is transferred to the vapors rising from the liquid fuel. These vapors will rise upwardly into the sleeves 23' and 47 and will be admixed with air entering through the perforations in said sleeves as well as with air which is directed upwardly through openings 43' in the pipe 43. The draft air emitting from the circular pipe 43 conducts or directs the vapors and air mixture upwardly through the ports 48 and 50 and into the casing 29'. The vapors which have entered the inner sleeve 47 rise through the opening 49 and strike the underside of the casing 29' and are then spread into the path of the upwardly moving mixture passing through the openings 50 and the bottom of the casing 29'. In this manner the flame is circular and tends to more evenly distribute the heat throughout the casing 29'.

While the bowl is shown circular, obviously it may be made in any shape such as a parallelogram or square or any shape desired.

What I claim and desire to secure by Letters Patent is:

1. A burner including, a housing having a vaporizing chamber therein, means for supplying a liquid fuel to said chamber, a combustion chamber above the vaporizing chamber and communicating therewith, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, means for introducing air circumferentially into the combustion chamber whereby said air admixes with the vapors therein to produce a combustible mixture therein, and means for directing an additional stream of air upwardly through the combustion chamber to assure sufficient air for a combustible mixture and also for creating a suction to draw the vapors from the vaporizing chamber and an air passageway leading into the upper portion of the combustion chamber so that a final supply of secondary air may be introduced into the burning vapors.

2. A burner including, a housing having a vaporizing chamber therein, means for supplying a liquid fuel to said chamber, a combustion chamber above the vaporizing chamber and communicating therewith, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, means for introducing air into the combustion chamber so as to admix with the vapors rising from the liquid fuel to produce a combustible mixture, an upper chamber mounted above the combustion chamber and communicating therewith, and means for directing a stream of air upwardly through the combustion chamber for forcing the burning mixture upwardly into the upper chamber and for creating a suction to draw the vapors from the vaporizing chamber and an air passageway leading into

the upper portion of the combustion chamber so that a final supply of secondary air may be introduced into the burning vapors.

3. A burner including, a housing having a vaporizing chamber therein, means for supplying a liquid fuel to said chamber, a combustion chamber above the vaporizing chamber and communicating therewith, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, means for introducing air into the combustion chamber so as to admix with the vapors rising from the liquid fuel to produce a combustible mixture, the disposition of said combustion chamber with relation to the vaporizing chamber being such that the heat of the burning mixture within the combustion chamber vaporizes the liquid fuel in the vaporizing chamber, an upper chamber mounted above the combustion chamber and communicating therewith, and means for directing a stream of air upwardly through the combustion chamber for forcing the burning mixture upwardly into the upper chamber and for creating a suction to draw the vapors from the vaporizing chamber and an air passageway leading into the upper portion of the combustion chamber so that a final supply of secondary air may be introduced into the burning vapors.

4. A burner including, a housing having a vaporizing chamber therein, means for supplying a liquid fuel to said chamber, a combustion chamber above the vaporizing chamber and communicating therewith and formed of a plurality of tiers reduced toward the upper end thereof, each tier having air admitting openings therein which increase in number toward the top of the chamber, means for supplying sufficient air to the vaporizing chamber to permit burning of the liquid fuel upon the initial operation of the burner, and means for restricting the supply of air to said vaporizing chamber when sufficient heat for vaporization of the liquid fuel is attained, whereby further combustion in the vaporizing chamber is impossible, the vapors from said chamber rising into the combustion chamber and being gradually admixed with an increased amount of air as they rise therein until a combustible mixture is produced at which time said mixture ignites and burns.

5. A burner including, a housing having a vaporizing chamber therein, means for supplying a liquid fuel to said chamber, a combustion chamber above the vaporizing chamber and communicating therewith and formed of a plurality of tiers reduced toward the upper end thereof, each tier having air admitting openings therein which increase in number toward the top of the chamber, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, the vapors from said chamber rising into the combustion chamber and being gradually admixed with an increased amount of air as they rise therein until a combustible mixture is produced at which time said mixture ignites and burns, and means for directing an additional

stream of air upwardly through the combustion chamber to assure sufficient air for a combustible mixture and also for creating a suction to draw the vapors from the vaporizing chamber.

5 6. A burner including, a housing having a vaporizing chamber therein, means for supplying a liquid fuel to said chamber, a combustion chamber above the vaporizing chamber and communicating therewith and formed of a plurality of tiers reduced toward the upper end thereof, each tier having air admitting openings therein which increase in number toward the top of the chamber, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, the vapors from said chamber rising into the combustion chamber and being gradually admixed with an increased amount of air as they rise therein until a combustible mixture is produced at which time said mixture ignites and burns, means for directing an additional stream of air upwardly through the combustion chamber to assure sufficient air for a combustible mixture and also for creating a suction to draw the vapors from the vaporizing chamber, and a heater casing mounted above the combustion chamber and communicating therewith.

7. A burner including, a housing having a vaporizing chamber therein, means for supplying a liquid fuel to said chamber, a combustion chamber above the vaporizing chamber and communicating therewith and formed of concentric sleeves having air admitting openings therein, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, the vapors from said chamber rising into the combustion chamber and being gradually admixed with an increased amount of air as they rise therein until a combustible mixture is produced at which time said mixture ignites and burns, and a circular air admitting pipe underlying the annular space between the concentric sleeves for directing a stream of air upwardly of the combustion chamber to force the combustible mixture upwardly therethrough and also for drawing vapors from the vaporization chamber into the combustion chamber.

8. A burner including, a housing having a vaporizing chamber therein, means for supplying a liquid fuel to said chamber, a combustion chamber above the vaporizing chamber and communicating therewith and formed of concentric sleeves having air admitting openings therein, means for supplying sufficient air to the vaporizing chamber to permit burning of the liquid fuel upon the initial operation of the burner, means for restricting the supply of air to said vaporizing chamber when sufficient heat for vaporization of the liquid fuel is attained, whereby further combustion in the vaporizing chamber is impossible, the vapors from said chamber rising into the combustion chamber and being gradually admixed with an increased amount of air as they rise therein until a combustible mixture is produced at which time said mixture ignites and burns, a heater casing mounted above the

combustion chamber and communicating therewith, and a circular air admitting pipe underlying the annular space between the concentric sleeves for directing a stream of air upwardly of the combustion chamber to force the combustible mixture upwardly therethrough into said heater casing and also for drawing vapors from the vaporization chamber into the combustion chamber.

9. A three stage burner including a vaporizing casing, a combustion chamber and an upper chamber, means to introduce liquid fuel in the casing, openings in said casing whereby an inadequate amount of air to support combustion is introduced into the casing and mixed with the vaporized fuel therein, means to introduce an initial supply of secondary air into the vaporized fuel in the combustion chamber, means to introduce a final supply of secondary air in the vaporized fuel while it is passing from the combustion chamber into the upper chamber and means to introduce and direct upwardly a supply of air in the center of the lower portion of the combustion chamber.

10. A burner including, a housing, having a vaporizing chamber therein, means for supplying a liquid fuel to said chamber, means for introducing a limited amount of air, insufficient to support combustion, into said vaporizing chamber, a combustion chamber above and communicating with the vaporizing chamber whereby the vaporized fuel from the vaporizing chamber rises thereto, means for introducing air into the combustion chamber so as to admix with the vaporized fuel and form a combustible mixture within said combustion chamber, means to introduce a supply of secondary air into the vapors in the central portion near the bottom of the combustion chamber, means to introduce a secondary supply of air into the burning vapors as they are passing from said combustion chamber, the disposition of said combustion chamber with relation to the vaporizing chamber being such that the heat of the burning mixture within the combustion chamber vaporizes the liquid fuel in the vaporizing chamber.

RICHARD S. MOORE.
